Primary Examiner — Leanne Was-Englehart(74) *Attorney, Agent, or Firm* — Knobbe, Martens, Olson & Bear, LLP(57) **CLAIM**

The ornamental design for a fender flare, as shown and described.

DESCRIPTION

FIG. 1 is a front perspective view of a fender flare;
FIG. 2 is an enlarged view of a portion of the fender flare of FIG. 1 shown in area designated 2 in FIG. 1;
FIG. 3 is a bottom rear perspective view thereof;
FIG. 4 is a front elevational view thereof;
FIG. 5 is a rear elevational view thereof;
FIG. 6 is a left elevational view thereof;
FIG. 7 is a right elevational view thereof;
FIG. 8 is a top plan view thereof; and,
FIG. 9 is a bottom plan view thereof.
Broken lines are used to illustrate features of the fender flare which form no part of the claimed design.
